UNITED STATES PATENT OFFICE.

JOHN L. COONEY, OF ERIE, PENNSYLVANIA.

BEATER ROLL.

Application filed February 2, 1925. Serial No. 6,282.

To all whom it may concern:

Be it known that I, JOHN L. COONEY, a citizen of the United States, residing at Erie, in the county of Erie and State of Pennsylvania, have invented new and useful Improvements in Beater Rolls, of which the following is a specification.

This invention is designed to improve and simplify the construction of beaters, particularly such beaters as are used in paper making. It has to do more particularly with the manner of securing the beater blades and the inserts between the blades.

The invention is illustrated in the accompanying drawings as follows:—

Fig. 1 shows a central vertical section through the beater.

Fig. 2 a section on the line 2—2 in Fig. 1.

Fig. 3 a section on the line 3—3 in Fig. 1.

Fig. 4 a section on the line 4—4 in Fig. 1.

Fig. 5 an end view of one of the cover plates.

Fig. 6 an enlarged view of one of the plate securing bolts.

Fig. 7 a perspective view of one of the securing wedges.

Fig. 8 a perspective view of the bolt locking segment.

1 marks the shaft on which the beater is mounted, 2 end webs or discs mounted on the shaft, and 3 a central disc. Arranged around the disc are the blade rings 4, these rings having the axial slots 5 extending through them. An annular shoulder 5^a extends from the rings and this shoulder is free of obstructions on its outer surface so that it may be readily machined. Blades 6 are arranged in the slots 5 and rest on the shoulders 5^a, the shoulders forming a base for the plates.

Wedge blocks 7 are arranged between the blades 6 and these blocks form the heads of bolts 8, the bolts extending through the shoulders 5^a on the end rings and are provided with nuts 9 on the inner periphery of the rings by which the wedge blocks may be drawn in, thus securing the blades and seating them on the shoulders. The blades are preferably slightly thicker at their inner edges than at their outer edges and thus assist the wedge blocks in locking them in place.

On the central web bolts 10 extend through the shoulder 5^a, the heads 11 of these bolts being arranged in pockets in the locking ring 12, the locking ring being

formed in segments with ears 13 and are secured to the shoulder by screws 14 extending through the ears 13. With this construction the bolts are put in place and locked against turning by the locking plate. Wedge blocks 15 are arranged between the blades outside the shoulder 5^a on the web 3. These blocks have the sockets 16 which receive the nuts 17 so that the blocks may be tightened by clamping the blades in place at the center.

Plates 19 are arranged on the outer faces of the outer webs 2 covering the bolts 9.

Wooden strips 18 are arranged between the blades and between the webs. These correspond in shape and in location radially with the wedge blocks 7 and 15.

What I claim as new is:—

1. In a beater roll, the combination of 75 supporting rings having slotted rims and base shoulders extending from the rims; blades in the slots; and bolts extending through the shoulders and having wedge-shaped heads between the blades. 80

2. In a beater roll, the combination of 85 supporting rings having slotted rims and base shoulders extending from the rims; blades in the slots resting on the shoulders; and bolts extending through the shoulders and having wedge-shaped heads between the blades.

3. In a beater roll, the combination of 90 rings having slotted rims and base shoulders extending axially from the rims; blades in the slots; bolts extending through the shoulders and having wedge-shaped heads between the blades; and wood strips between the blades having their outer surfaces flush with the ends of the bolt heads. 95

4. In a beater, the combination of two 100 end supporting rings and an intermediate supporting ring, said rings having slotted rims and shoulders extending axially therefrom; beater blades arranged in the slots; bolts extending radially through the shoulders of the intermediate ring having heads within the ring; wedge blocks between the blades through which the bolts extend; and nuts on the bolts operating on the blocks. 105

5. In a beater, the combination of two 110 end supporting rings and an intermediate supporting ring, said rings having slotted rims and shoulders extending axially therefrom; beater blades arranged in the slots; bolts extending radially through the shoulders of the intermediate ring having heads

within the ring; wedge blocks between the blades through which the bolts extend; and nuts on the bolts operating on the blocks, said blocks having sockets for receiving the nuts.

6. In a beater, the combination of two end supporting rings and an intermediate supporting ring, said rings having slotted rims and shoulders extending axially therefrom; beater blades arranged in the slots; bolts extending radially through the shoulders of the intermediate ring having heads within the ring; wedge blocks between the blades through which the bolts extend; nuts on the bolts operating on the blocks; and means within the shoulder for locking the bolts against turning.

7. In a beater, the combination of two end supporting rings and an intermediate supporting ring, said rings having slotted rims and shoulders extending axially therefrom; beater blades arranged in the slots; bolts extending radially through the shoulders of the intermediate ring having heads within the ring; wedge blocks between the

blades through which the bolts extend; nuts on the bolts operating on the blocks; and means within the shoulder for locking the bolts against turning comprising a notched plate secured to the ring.

8. In a beater roll, the combination of two end rings and an intermediate ring, said rings having slotted rims and base shoulders extending axially from the rims; blades in the slots resting on the shoulders; bolts extending through the shoulders of the end rings, said bolts having wedge-shaped heads between the blades; bolts extending through the shoulder of the intermediate ring with the heads within the ring; means for operating on the heads for locking said last-mentioned bolts against turning; wedge-shaped blocks between the blades through which the outer end of the last-mentioned bolts extend; and nuts on said bolts operating on said blocks.

In testimony whereof I have hereunto set my hand.

JOHN L. COONEY.
